Patented Dec. 26, 1916.

UNITED STATES PATENT OFFICE.

WILLIAM B. HIDDEN, OF BOSTON, MASSACHUSETTS.

CARBURETER.

1,210,169.

Specification of Letters Patent. Patented Dec. 26, 1916.

Application filed June 15, 1915. Serial No. 34,537.

To all whom it may concern:

Be it known that I, WILLIAM B. HIDDEN, a citizen of the United States, and resident of Boston, in the county of Suffolk and 5 State of Massachusetts, have invented certain new and useful Improvements in Carbureters, of which the following is a specification.

This invention relates to carbureters, and 10 its purpose is to simplify the construction of such devices and to direct the air current in such manner as to insure the necessary evaporation of the hydrocarbon vapor. The evaporation of the hydrocarbon takes place 15 exclusively in a chamber in which a constant volume of liquid hydrocarbon is maintained in an inert condition. By "inert" I mean that it is not precipitated and that no atomization or other motion of the hydrocarbon 20 liquid is required. The air current is guided and deflected by specially formed surfaces in the said chamber, whereby it is caused to swirl upon the surface of the liquid hydrocarbon, in this way being caused to absorb 25 the hydrocarbon vapor to such extent that a combustible vapor free from liquid atoms will be insured.

Of the accompanying drawings, which 30 illustrate one form in which the invention may be embodied: Figure 1 represents a top plan view of a carbureter provided with a float valve arranged to control automatically the supply of liquid hydrocarbon. Fig. 2 represents a vertical section through the carbureter, as indicated by line 2-2 of Fig. 1. Fig. 3 represents a vertical cross section in the plane indicated by line 3-3 of Fig. 1. Fig. 4 represents an end elevation of the right hand end, with reference to Figs. 1 35 and 2. Fig. 5 represents an elevation projected from Fig. 1.

The same reference characters indicate the same parts wherever they occur.

The casing 10 of the carbureter is divided 45 to provide a supply chamber 11 and an evaporating chamber 12. Liquid hydrocarbon 13 is fed into the chamber 11 and conducted from the latter to the chamber 12 through a passageway which includes a duct 50 14 and a tube 15, the latter extending upwardly a substantial distance from the bottom of the chamber. The supply of liquid hydrocarbon enters the chamber 11 through a passageway 16, to which it may be conducted 55 from a reservoir by a pipe, not shown.

The feeding of liquid hydrocarbon into the chamber 11 is controlled by a valve 17 which is operated by a float 18. The fulcrum of the float is indicated at 19, and the 60 float lever which actuates the valve is indicated at 20. The purpose of the valve and the float is to maintain a constant volume of liquid hydrocarbon in the chambers 11 and 12; and so long as the valve and float 65 are arranged to operate in such manner, their form and details are optional.

The purpose in arranging the tube 15 to project upwardly from the bottom of the mixing chamber is to prevent the liquid 70 hydrocarbon from running back by gravity into the supply chamber when the carbureter is tipped. I have shown a body of absorbent material 21 in the bottom of the chamber 12. One purpose of the element 21 is to minimize 75 the splashing of the liquid hydrocarbon. For this purpose it is not necessary that the anti-splashing element have any absorptive capacity, although I prefer an absorbent element for the reason that it will hold some 80 of the liquid when the carbureter is inverted.

The shape of the evaporating chamber is preferably cylindric, and it is so shown. The axis of the chamber is vertical when 85 the carbureter is in its normal position, as shown. This chamber has an air-inlet passageway 22, and an outlet passageway 23. The walls of these passageways have peculiar formations by which the incoming current 90 of air is caused to swirl around the axis of the chamber in the manner of a whirlwind, and whereby the vortex of air is deflected downwardly upon the surface of the liquid hydrocarbon with force enough 95 to insure the absorption by air of the necessary volume of hydrocarbon vapor. It will be understood that the flow of air through the chamber is caused by the suction of the internal combustion engine to which the carbureter is applied. 100

Referring to Fig. 1, the current of air entering the inlet 22 will be deflected by the surface 24 so that it will be caused to flow circumferentially of the evaporating chamber. For a considerable portion, in the present instance slightly more than 180 degrees, of the circumference of the chamber, the incoming current of air is inclosed in a duct 25 (see Figs. 2 and 3) which extends 110 circumferentially along the inner side of the casing. The discharge end of the inlet

duct is indicated at 26 in Figs. 1 and 3. This duct curves downwardly as shown by Figs. 3 and 5, in addition to extending circumferentially, thus directing the current 5 of air according to the form of a helix. The air, upon leaving the inlet duct, absorbs the hydrocarbon vapor in the chamber and is conducted from the latter to the outlet 10 23 through a duct 27 whose receiving end is indicated at 28 in Figs. 1 and 5. This duct also extends circumferentially upon the interior of the casing 10, and is of helical formation, as shown by Figs. 2, 3 and 5. The desired absorption of the hydrocarbon 15 vapor is promoted by the conjoint deflecting action of the circumferential internal surface 29 of the casing 10 and the helicoidal bottom surface 30 of the outlet duct, these two surfaces forming an angle, as clearly 20 shown by Figs. 2 and 3, into which the current of air is delivered by the inlet duct. The swirling action of the air in passing from the inlet duct to the outlet duct is continued by the surface 29, and, at the same 25 time, the air current is deflected downwardly by the surface 30. The effect of the surface 30 is to precipitate the air against the surface of the liquid hydrocarbon, and the air is thus forced to travel upon the surface of 30 the liquid for a substantial distance, in the present instance approximately 180 degrees of the circumference of the chamber. The lower end of the surface 30 is relatively close to the surface of the liquid hydrocarbon, and 35 the current of air in traversing the surface 30 is necessarily spread toward the axis of the cylinder so that a relatively great proportion of the air is brought into contact with the surface of the liquid. A substantial 40 part of the area of the chamber is occupied by hydrocarbon vapor, and the latter is absorbed by the air which does not come into contact with the hydrocarbon liquid.

Under all conditions, the swirling action caused by the circumferential surface 29 45 and the downward deflection caused by the surface 30 insures sufficient absorption of vapor. There is no spraying or atomizing of liquid hydrocarbon, and only the vapor of the hydrocarbon is carried off by the current of air. 50

I have shown a throttle valve 31 arranged to control the inlet of air, and a throttle valve 32 arranged to control the flow of combustible mixture from the carbureter. 55 The provision or omission of these valves is optional, and their form is also optional. The evaporating chamber has a cover 33, and the supply chamber has a cover 34, the two chambers being thus closed with the exception of the inlets and outlets hereinbefore specified, and the carbureter is therefore especially adapted for use in aeroplanes, because it will operate in all positions, even though it be completely inverted. With special reference to its operation when inverted, the absorbent material 21 is desirable because it will retain by capillary action a sufficient quantity of liquid hydrocarbon in the path traversed by the air current to insure a continuation of the absorption of vapor by the air until the aeroplane can be righted. 60 70

I claim:

A carbureter comprising an evaporating 75 chamber having a substantially circular up-standing wall, means arranged to maintain a pool of liquid hydrocarbon in said chamber, an air inlet duct arranged to emit the air contiguous to and circumferentially of 80 said wall, and an outlet duct arranged to deflect downwardly the air emitted from said inlet duct.

In testimony whereof I have affixed my signature.

WILLIAM B. HIDDEN.
